Inventor:
Bruno Paul Frieden,
By *Henryorth Jr.* atty.

UNITED STATES PATENT OFFICE.

BRUNO PAUL FRIEDEN, OF HAMBURG, GERMANY.

SURGICAL TRUSS.

1,387,774.

Specification of Letters Patent. Patented Aug. 16, 1921.

Application filed January 23, 1918. Serial No. 213,441.

To all whom it may concern:

Be it known that I, BRUNO PAUL FRIEDEN, citizen of Hamburg, in the German Empire, residing at Hamburg, Germany, have invented certain new and useful Improvements in Surgical Trusses, of which the following is a specification.

The surgical or hernial trusses known heretofore have the drawback that the belt owing to its usual position on the back and on the back-muscles and nerves exerts an annoying pressure. This pressure frequently increases to such an extent that it cannot be endured, because the belt presses 10 on those bony parts of the body, projecting intermediate of the third and fourth sacral vertebrae from the coccyx, which project more than other bony parts. The said parts will protrude still more when the patient 15 bends his back or carries out other movements. In consequence of such movements the belt or truss is displaced from its proper position so that it hinders the free movement and thus increases the inconvenience in using 20 the truss and at the same time failing in its 25 object and its effect.

The object of the present invention is to do away with these drawbacks and this is accomplished by moving the back part of 30 the belt from the usual position to a position higher up. In this case the pressure of the belt is distributed over a part of the back, where no vertebrae project and the back part of the belt will be in a position, in which 35 the movements of the body, such as the bending of the spine, will have no effect on the belt, so that the truss remains unaltered and in its proper position, and all shifting of it is prevented. The proper position is 40 also moreover secured by the fact that the lateral parts of the belt remain in the lower line necessary for the convenient and invariable fitting of the truss on the body of the patient.

By way of example a double truss is 45 shown in Figure 1 of the drawing in a perspective view. Figs. 2, 3, 4 and 5 show modifications of the invention.

The back part a^1 of the belt a , in which 50 is embedded a spring c , is so shaped that it is offset at b , b at the back in such manner that the said back part a^1 lies a certain distance above and parallel to the remaining parts a^2 of the belt. The said back part a^1 55 and the belt parts a^2 are unyielding in the planes of the bearing surfaces, however, they

snugly adjust themselves to the shape of the body. The inflexibility of the back part a^1 and the other parts a^2 of the belt in their planes is due to the fact that the spring c is 60 flat in cross section.

The off setting of the spring c can be carried out in different ways. In Fig. 1 it is understood that the back part c^1 of the spring c together with the offsets b^1 and the 65 front parts c^2 of the spring are all made integral, cut from one piece, however, this being rather expensive, it is preferred to make the truss spring in sections and to fasten them together.

In Fig. 2 the back part c^1 is made integral with the offsets or angular pieces b^1 , which are riveted or otherwise fastened to the front parts c^2 of the spring. In Fig. 3 a special preferably rectangular plate b^2 is 75 riveted to the back part c^1 and the front part c^2 of the spring. In Fig. 4 a Z-shaped plate is used for the setoff part b^1 , thus forming lateral prolongations on the top and bottom for securely riveting to the back part c^1 80 and the front parts c^2 . In Fig. 5 an angular plate b^4 is shown for a similar purpose, having only one end provided with a lateral prolongation.

The pads e in the double truss shown are 85 attached to the ends of the belt parts a^2 . The belt parts a^2 can be connected at the angular offsets b by a strap d . To enable this, each belt part a^2 can be provided at the angular offset with a button f and the 90 ends of the said strap are provided with a number of slits or holes g to enable the fastening of the strap to the buttons f , by means of which a tighter or looser adjusting of the truss can be effected. If preferred, 95 the middle part of the strap d may be cushioned by a patch h of softer material.

The button f may be either attached to the front parts of the spring, as shown in Fig. 1 or it may be attached to the special 100 plate b^1 , as shown in Fig. 3.

For so called springless trusses the front part c^2 of the spring may be omitted and merely a prolongation of the plate b^1 may project into that particular belt part, as 105 shown in Fig. 5.

A truss made according to the above explained invention will invariably remain in its proper position when the patient is walking, sitting, lying or standing and will not 110 exert an annoying pressure at any place. More particularly it prevents irritation of

the ischiatic nerve. Owing to the displacement of the back part of the belt with regard to the side parts of the belt, sensitive parts of the spine are not touched, but the pressure of the belt is, without impairing the proper fitting, removed to a higher part of the back, where the pressure is not inconvenient and where no change in the position of the bony parts takes place, which would cause inconvenience and render the movement difficult.

I claim:

1. A truss frame consisting of a plurality of sections, flat in the same general plane, one of said sections adapted to extend across the human back, and two sections adapted

to run across the hips and connected to the ends of the back section by upwardly extending sections.

2. A truss frame consisting of a plurality of sections flat in the same general plane, one of said sections adapted to extend across the human back, two sections adapted to run across the hips and connected to the ends of the back section by upwardly extending sections, and a strap connecting the hip sections at the lower ends of the upwardly extending sections. 20 25

BRUNO PAUL FRIEDEN.
